COMBINED STORAGE BOWL AND SERVING PLATE

Erik Herlow, Tikob, Denmark, and Robert Daenen,
Erembodegem, Belgium, assignors to Dart Industries
Inc., Los Angeles, Calif.

Filed Jan. 18, 1974, Ser. No. 434,738

Term of patent 14 years

Int. Cl. D7—01

U.S. Cl. D7—17

FIG. 2.

2 →

FIG. 1.

FIG. 3.

FIG. 4.

FIG. 1 is a side elevational view of a combined storage bowl and serving plate showing our new design;

FIG. 2 is a sectioned elevational view of the combined storage bowl and serving plate taken along line 2—2 of FIG. 1;

FIG. 3 is a top plan view of the serving plate thereof on a reduced scale;

FIG. 4 is a bottom plan view of FIG. 3;

FIG. 5 is a top plan view of the storage bowl thereof on a reduced scale; and

FIG. 6 is a bottom plan view of FIG. 5.

We claim:

The ornamental design for a combined storage bowl and serving plate, substantially as shown.
